(57) **CLAIM**

I claim the ornamental design for a O-ring spreading pliers, as shown and described.

DESCRIPTION

FIG. 1 is a front view of the O-ring spreading pliers.
FIG. 2 is a back view of the claimed design.
FIG. 3 is a side view of the claimed design.
FIG. 4 is a top view of the claimed design; and,
FIG. 5 is a bottom view of the claimed design.

1 Claim, 3 Drawing Sheets

FIG. 1

FIG. 2

FIG. 3

FIG. 4

FIG. 5
